INSTRUMENT CABINET

William E. Reeves, Three Tuns, and Joseph F. Larkin,
Philadelphia, Pa.; said Larkin assignor to said Reeves

Application October 2, 1956, Serial No. 43,188

Term of patent 14 years

(Cl. D26—1)

FIG. 1.

FIG. 2.

Figure 1 is a perspective view of an instrument cabinet, showing our new design with the hinged cover in closed position; and

Figure 2 is a perspective view thereof with the hinged cover in open position.

The broken line showing of an electronic instrument chassis is for illustrative purposes only.

We claim:

The ornamental design for an instrument cabinet, as shown and described.
